[57] CLAIM

The ornamental design for a display stand or similar article, as shown.

DESCRIPTION

FIG. 1 is a side elevational view from a first direction of a display device showing our new design;

FIG. 3 is a side elevational view of the display device of FIG. 1 taken from a second direction from the right of and orthogonal to said first direction;

FIG. 4 is a top plan view of the display device of FIGS. 1 and 3; and

FIG. 5 is a view in section of the lower portion of the display device of FIGS. 1 and 3.
